UNITED STATES PATENT OFFICE.

GOODRIDGE B. WILSON, OF CAMDEN, TEXAS, ASSIGNOR OF ONE-HALF TO LILLIE BELLE SHOTWELL, OF CROCKETT, TEXAS.

AUTOMATIC WATER CUT-OFF.

1,246,368.

Specification of Letters Patent. Patented Nov. 13, 1917.

Application filed August 16, 1916. Serial No. 115,222.

To all whom it may concern:

Be it known that I, GOODRIDGE B. WILSON, a citizen of the United States, residing at Camden, in the county of Polk and State 5 of Texas, have invented certain new and useful Improvements in Automatic Water Cut-Offs; and I do hereby declare the following to be a full, clear, and exact description of the invention, such as will enable others 10 skilled in the art to which it appertains to make and use the same.

The invention relates to an automatic water cut off.

The object of the present invention is to 15 provide a simple, practical, and comparatively inexpensive water cut off of strong and durable construction adapted to be readily applied to water pipes and adapted in event of the falling of the temperature to 20 freezing or any other predetermined degree of automatically cutting off the flow of the water and of draining the pipe to prevent the bursting of the same through freezing of water contained therein.

25 Another object of the invention is to provide means for automatically venting the pipe to permit the water to flow freely through the waste outlet of a cut off when the latter is closed.

30 With these and other objects in view the invention consists in the construction and novel combination and arrangement of parts hereinafter fully described, illustrated in the accompanying drawings and pointed out in 35 the claims hereto appended, it being understood that various changes in the form, proportion and minor details of construction may be resorted to without departing from the spirit or sacrificing any of the advantages of the invention.

40 In the drawing,

Figure 1 is a side elevation partly in section of an automatic water cut off constructed in accordance with this invention,

45 Fig. 2 is a detail perspective view of the support for the movable valve actuating weight.

50 Like numerals of reference designate corresponding parts in all the figures of the drawing.

In the accompanying drawing in which is illustrated the preferred embodiment of the invention, 1 designates a stop or cut off valve of the ordinary construction having a waste 55 outlet 2 adapted to drain the water in the pipe 3 at the discharge side of the valve 1 when the latter is closed. The cut off and waste valve 1 is of the ordinary construction, and as no claim is made for the particular construction of the valve and furthermore 60 as any construction of cut off and waste valve may be employed specific description thereof and illustration of the details of the same are believed to be unnecessary. The cut off and waste valve is connected with a 65 water supply or feed pipe 4 at the pressure side and it is provided with an operating arm 5 which is arranged in a horizontal position when the valve is open to permit the water to flow freely from the pipe 4 into the 70 pipe 3.

The arm 5 is adapted to be swung upwardly from a horizontal position to close the cut off valve and it is connected to the lower end of a cord 6 or other flexible connection such as a wire or the like which passes over an overhead pulley or guide 7. The other end of the flexible connection 6 is attached to a movable valve actuating member 8 normally supported upon the upper 80 end of a post 9 or other suitable supporting device and adapted to be unbalanced or upset by a thermostatic device whereby the weight is caused to fall and swing the arm 5 upwardly to its closed position. The post 85 9 is provided a short distance below its upper end with a shelf or supplemental support 10 arranged to receive the weight when it falls from the upper end of the support 9 as illustrated in Fig. 1 of the drawing. 90 This will relieve the valve of strain and will enable a weight of sufficient size to be employed to secure a positive operation of the cut off valve in its closing movement without liability of injuring the valve or the plumbing 95 when the weight falls.

The weight is unbalanced or upset by means of a thermostatic device comprising a thermometer 11 having a tube 12 containing a mercury column 13 and receiving a 100 rod or stem 14 of a piston having a head 15 constituting a weight. The piston rod or stem 14 snugly fits the tube 12 and is supported by the mercury column and when the mercury contracts through the lowering of 105 the temperature the weight or head 15 will descend and engage an arm 16 of the valve actuating weight 8. The arm 16 is horizontally disposed and extends from the weight 8 at the bottom thereof and is arranged in 110 the path of a set screw or adjusting screw 17 mounted in a threaded opening of a lug

or ear 18 of the head or weight of the piston. The adjusting screw is vertically disposed and it is adapted to permit a fine adjustment of the thermostatic device so that 5 the weight will be upset or unbalanced at the proper degree indicated by the thermometer. While it is preferable to employ a thermostatic device of the form shown, any other construction of thermostatic device 10 may of course be used for displacing the weight. In order to permit the water in the pipe 3 to be drained therefrom through the waste valve of the cut off the pipe 3 is provided with an automatic air inlet 15 valve preferably mounted in the barrel 19 of the bib cock 20 but it may be applied to the pipe 3 at any other desired point and may be constructed independently of the bib cock as will be readily understood. 20 The tubular body portion or barrel 19 is provided at the top with an opening and it has an annular flange 21 extending upwardly from the opening and an inclined downwardly tapered annular flange 22 depending 25 from the opening. The upwardly extending annular flange 21 is interiorly threaded at 23 to receive a plug 24 provided with an exterior shoulder 25 and having a conical recess in its lower face communicating at 30 its apex with an air inlet opening 27. The tapered recess 26 forms a guard for the plunger valve 28 consisting of a conical head adapted to fit the recess 26 and provided with a concaved lower face forming a recess 35 and adapted to receive the fluid pressure whereby it will be closed by internal pressure before any of the water flowing into the barrel will escape through the air inlet or vent opening 27. The downwardly and 40 inwardly inclined flange 22 forms a contracted opening and insures the water acting upon the lower concaved face of the plunger valve to effect a closing of the valve before any leakage of the water can occur 45 through the vent opening. The plunger valve is provided with a vertical stem 30 depending centrally from the said valve and passing through upper and lower guides 31 and 32. 50 The upper and lower guides are in the form of spiders which are provided with central openings through which the stem slides. A suitable washer or gasket may be arranged between the shoulder of the plug 55 and the upper edge of the flange 21 and the outer portion of the plug of the air inlet valve will be polygonal to receive a wrench. No claim is made in the present application to the specific construction of the air inlet 60 valve as the same forms the subject matter of a co-pending application executed of even date herewith.

When the cut off valve is closed and the

waste outlet is opened air pressure on the plunger valve of the air inlet device will 65 open the plunger valve and cause the water to flow freely through the waste outlet as the air is adapted to pass around the plunger valve which is supported in its open position in spaced relation with the flange 22. 70

What is claimed is:—

1. An automatic water cut off including a combined cut off and waste valve having an operating arm, a weight, means for supporting the weight in an elevated position, 75 means for connecting the weight with the cut off and waste valve for closing the cut off valve and opening the waste outlet when the weight falls and a thermostatic device provided with means for displacing the 80 weight to cause the same to fall, and a supplemental support arranged to receive the weight for limiting the downward movement of the same whereby the cut off and waste valve will be relieved of strain after 85 the cut off valve has been closed.
2. An automatic water cut off including a combined cut off and waste valve having an operating arm, a weight, a post for supporting the weight in an elevated position, 90 an overhead guide, a flexible connection arranged in the guide and connected with the weight and with the arm of the said valve and a thermostatic device for displacing the weight.
3. An automatic water cut off including a combined cut off and waste valve having an operating arm, a weight, a post for supporting the weight in an elevated position, 95 an overhead guide, a flexible connection arranged in the guide and connected with the weight, and with the arm of the said valve, a thermostatic device for displacing the weight, and a shelf mounted on the post and forming an auxiliary support for the 100 weight to relieve the valve of strain after the said valve has been closed.
4. An automatic water cut off including a combined cut off and waste valve, a weight, means for supporting the weight 110 in an elevated position, means for operatively connecting the weight with the said valve for closing the same when the weight falls, an arm extending from the weight, and a thermostat including a thermometer 115 having a mercury column and a piston supported by the mercury column and provided with a head, said head constituting a weight and having means for engaging the said arm to displace the weight.

In testimony whereof I affix my signature in presence of two witnesses.

GOODRIDGE B. WILSON.
